UNITED STATES PATENT OFFICE.

WILLIAM H. RANDLE AND BENJAMIN D. PHILLIPS, OF PHILADELPHIA,
PENNSYLVANIA.

DESIGN FOR A CAN-OPENER.

SPECIFICATION forming part of Design No. 30,502, dated April 4, 1899.

Application filed April 25, 1898. Serial No. 678,808. Term of patent 31 years.

To all whom it may concern:

Be it known that we, WILLIAM H. RANDLE and BENJAMIN D. PHILLIPS, citizens of the United States, residing at Philadelphia, (Germantown,) in the county of Philadelphia and State of Pennsylvania, have invented a new and original Design for Can-Openers; and we do hereby declare the following to be a full, clear, and exact description of the invention, such as will enable others skilled in the art to which it appertains to make and use the same.

Our invention relates to a design for a can-opener, reference being had to the accompanying drawings, in which—

Figure 1 is a top plan view. Fig. 2 is a side elevation, and Fig. 3 is a bottom plan view.

As shown in said drawings, the design consists of a handle *a*, bent downward and forward at a point *a'*, said handle terminating

in a substantially circular head *b*, from which extends the second handle *d*, having a slot *e* running longitudinally thereof for a part of its length, the sides of said slot countersunk, as shown at *e'*. The lower portion of the head *b* is circular in form and projects beyond the surface of the handle *d* and is provided with three sharpened prongs or pins *g*, projecting therefrom, substantially as shown.

Having thus described our invention, what we therefore claim as new, and desire to secure by Letters Patent, is—

The design for a can-opener substantially as herein shown and described.

WILLIAM H. RANDLE.
BENJAMIN D. PHILLIPS.
